UNITED STATES PATENT OFFICE.

CHARLES OSBORNE, OF NEW YORK, N. Y., ASSIGNOR TO THE WHITING MANUFACTURING COMPANY, OF SAME PLACE.

DESIGN FOR A SPOON OR SIMILAR ARTICLE.

SPECIFICATION forming part of Design No. 20,910, dated July 7, 1891.

Application filed June 4, 1891. Serial No. 395,118. Term of patent 3½ years.

To all whom it may concern:

Be it known that I, CHARLES OSBORNE, a citizen of the United States, residing at New York, in the county and State of New York, have invented and produced a new and original Design for a Handle for Flat Ware, of which the following is a specification.

Reference is to be had to the accompanying drawing, forming a part of this specification, in which the figure is a front view of a spoon the handle of which shows my design.

The leading feature of my design consists in the sitting figure of a man dressed in knickerbockers and ancient costume and with a pipe in his mouth, produced upon the handle.

The shank of the handle is an unbroken line until it reaches a point near the head, and here the side lines of the shank merge

in outwardly-curved lines which extend to the head, the top of which is scalloped. Between the outwardly-curved lines is the figure of a man dressed in knickerbockers and ancient costume, representing one of the settlers of Nieu Amsterdam. The pose of the man accords with Irving's description of the early settlers. Consequently he is represented as in a sitting posture and evidently smoking and in deep thought. The figure is surmounted by the colonial coat of arms of Nieu Amsterdam.

I claim—

The design for a handle for a spoon or similar flat ware herein shown and described.

CHARLES OSBORNE.
